COMBINED STAIRWAY RAILING, POSTS AND BRACKETS

Louis Blum, Pittsburgh, Pa.

Application October 18, 1956, Serial No. 43,397

Term of patent 14 years

(Cl. D13—7)

Figure 1 is a side elevational view of a combined stairway railing, posts and brackets showing my new design;

Figure 2 is an enlarged fragmentary sectional view in perspective taken from the right of Figure 1 with a portion of the post being broken away for convenience of illustration; and

Figure 3 is a cross-sectional view taken along the lines 3—3 of Figure 1.

The essential features of my design reside in the portions shown in full lines.

I claim:

The ornamental design for a combined stairway railing, posts and brackets, as shown and described.
